UNITED STATES PATENT OFFICE.

JULIAN G. GOODHUE, OF EVANSTON, AND HERBERT J. SAUVAGE, OF CHICAGO, ILLINOIS, ASSIGNORS TO ELECTRO THERMOSTATIC CONTROL COMPANY, OF CHICAGO, ILLINOIS, A COMMON-LAW TRUST.

ALARM-CLOCK SWITCH.

Application filed January 3, 1925. Serial No. 355.

This invention relates to an alarm clock control switch; the main objects of the invention are to provide a clock operated switch by means of which a circuit, such as a regulator circuit of a furnace control device may be rendered inoperative for a certain period of time, and may then be made operative at a predetermined time; to provide a switch which can be mounted on the alarm winding stem of an ordinary alarm clock; to provide a switch which is moved to the on-position by the clock mechanism when the alarm is released, and which may be manually moved to the off-position by rotating the alarm stem on re-winding the alarm.

An illustrative embodiment of this invention is shown in the drawings in which:

Figure 1 is an elevation of the regulator device in which the alarm clock and switch are incorporated.

Fig. 2 is a diagrammatic illustration of circuits in which the alarm clock switch is used.

Fig. 3 shows the switch and is taken on line 3—3 of Fig. 1.

Fig. 4 is a detailed section on the line 4—4 of Fig. 3.

In this invention a lever is secured to the handle of the alarm winding stems, and two stops are provided which limit the movement of the lever in either direction so that the alarm is wound and unwound the same amount at each operation. A mercury bulb switch is mounted in the lever so that it is tilted from the on-position when the alarm is set, to the off position when the alarm is released.

Since the clock mechanism is well-known, it is not shown in detail herein, but it is understood that the alarm winding stem operates in the usual manner, that is, the stem is rotated counter-clockwise to wind the alarm spring and is held in such position by a stop arrangement which is released by the alarm set mechanism in the clock. When the alarm is released, the stem then rotates clockwise as the alarm runs down.

Referring to Fig. 2, room thermostat

switch 1 is in series with the alarm clock 50 switch 2 in a circuit which controls the heating coil 4 and the solenoid 5 which are effective for operating the damper control lever 15 shown in Fig. 1, which is pivoted in the housing 14. The switch bulb 3, shown in 55 Fig. 2, is for controlling the furnace circuit and is operated by the solenoid 5.

As shown in Fig. 3, the clock 29 is fixedly mounted in the instrument housing and the alarm winding stem 31, the time winding 60 stem 32, and the regulating lever 33 are shown projecting from the back of the clock. The lever 30 is mounted on the handle of the alarm winding stem 31 and the lower end of the lever moves between the fixed 65 stops which are shown mounted on the casting of the control instruments. At the upper end of the lever and close to the axis of the stem is secured the mercury switch 2.

In the position shown in full lines, the 70 alarm has been released and the switch is closed. This is the position for daytime operation in such a circuit as shown in Fig. 2 wherein the clock switch is in series with the room thermostat switch.

At night, or when it is desired to stop the operation of the furnace for a predetermined period, the handle 30 is rotated to the position shown in dotted lines. This tilts the mercury bulb switch tube to the left and 80 opens the circuit to the room thermostat 1 and renders the room thermostat ineffective. The alarm is then set in the usual manner so that it is released at the time when it is desired to re-start the furnace.

It will now be seen that a very simple and practical form of clock control switch is provided. The switch can be mounted on an ordinary alarm clock and controlled by the alarm setting mechanism. The switch does 90 not in any manner interfere with the operation of the clock, since a very slight effort is required to tilt the switch from one position to the other.

While but one specific embodiment of this invention has been herein shown and described, it will be understood that numerous details of the construction shown may be

2
altered or omitted without departing from the spirit of this invention as defined by the following claim.

We claim:

- 5 In combination, a device of the class described, an alarm clock having an alarm winding stem which rotates when the alarm is released for unwinding, a mercury bulb

control switch mounted on said stem, and stops for limiting the rotation of said stem to an arc sufficient to tilt said bulb switch from "on" to "off" position. 10

Signed at Chicago this 29th day of December, 1924.

JULIAN G. GOODHUE.
HERBERT J. SAUVAGE.
